UNITED STATES PATENT OFFICE.

ALFRED HACHE, OF VIERZON, FRANCE.

DESIGN FOR A PLATE.

SPECIFICATION forming part of Design No. 22,780, dated September 12, 1893.

Application filed August 21, 1893. Serial No. 483,683. Term of patent 7 years.

To all whom it may concern:

Be it known that I, ALFRED HACHE, a citizen of France, residing at Vierzon, in the Department of Cher and Republic of France, 5 have invented and produced a new and original Design for Plates; and I do hereby declare the following to be a full, clear, and exact description of the same, reference being had to the accompanying drawing, forming a part 10 thereof.

The leading feature of my design consists in a plate with five concentric and elevated circular beads or ribs passing around the under side of the plate.

15 The accompanying figure represents a sectional view of my design. The outer circle A is a raised edge and passes around the periphery of the plate and is marked with a small and large elevation a a. The second 20 circular bead or rib B passes around the under side of the rim of the plate between the outer edge and the standard, and is marked |

by two elevations b b. The third circular bead or rib C like the first is marked by one small and one large elevation c c, and forms 25 the standard of the plate. The fourth circular bead or rib D is formed in the same manner as the second circle B and is placed at a short distance from the standard C, between that and the center of the plate d d. The fifth circular bead or rib E is formed in 30 the same manner as the bead or rib D and is placed between that and the center of the plate e e.

What I claim is—

35 A design for plates substantially as above shown and described.

In testimony whereof I affix my signature in presence of two witnesses.

ALFRED HACHE.
